UNITED STATES PATENT OFFICE.

JOSEPH M. MOLLOY, OF SPALDING, IDAHO.

DESIGN FOR A BADGE.

SPECIFICATION forming part of Design No. 33,205, dated September 18, 1900.

Application filed August 8, 1900. Serial No. 26,314. Term of patent 3½ years.

To all whom it may concern:

Be it known that I, JOSEPH M. MOLLOY, a citizen of the United States, residing at Spalding, in the county of Nez Perces and State of Idaho, have invented and produced a new and original Design for a Badge, of which the following is a specification.

This invention relates to a design for a badge; and the leading feature of the same consists in the design forming the subject-matter of the accompanying illustration, wherein—

Figure 1 is a plan view of the badge. Fig. 2 is a cross-section through the same.

The design is characterized by a body 1, having on one side the representation of land with a shore-line, as at 2, and adjacent the said line are two human figures 3 and 4, the figure 3 being in advance of the figure 4 and

pointing across a body of water, as at 5, to a third figure standing on an island 6, adjacent a flag-pole 7, having the flag of the United States at the peak thereof and the halyards grasped by the figure adjacent thereto. The figure 3 is in advance of the figure 4, and the latter is pointing a firearm at the figure adjacent the flag-pole.

Having thus described the invention, what is claimed as new is—

The design for a badge, herein shown and described.

In testimony that I claim the foregoing as my own I have hereto affixed my signature in the presence of two witnesses.

JOSEPH M. MOLLOY.
